UNITED STATES PATENT OFFICE.

FRANK LOUIS MILLER, OF PARKERSBURG, WEST VIRGINIA, ASSIGNOR TO PERFECTION
WOOD STEAMING RETORT CO., OF PARKERSBURG, WEST VIRGINIA, A CORPORATION
OF WEST VIRGINIA.

FASTENER FOR RETORT-DOORS.

1,262,226.

Specification of Letters Patent.

Patented Apr. 9, 1918.

Application filed July 30, 1917. Serial No. 183,636.

To all whom it may concern:

Be it known that I, FRANK LOUIS MILLER, a citizen of the United States of America, residing in Parkersburg, in the county of 5 Wood and State of West Virginia, have invented certain new and useful Improvements in Fasteners for Retort-Doors, of which the following is a specification.

This invention relates to fasteners for closures or doors for retorts or other containers of fluid under pressure, and aims to provide improvements therein.

The present invention provides a fastener for closure or door of the kind above referred to, which is of simple construction, effective in operation, and consisting of simple and readily assembled parts.

An embodiment of the invention is illustrated in the accompanying drawings, 20 wherein,—

Figure 1 shows a door on a retort, the door being in closed position, and viewed in front elevation;

Fig. 2 is a view similar to Fig. 1, the door 25 being viewed in rear elevation;

Fig. 3 is a cross-section on the line 3—3, Fig. 1.

In said drawings, numeral 1 designates the open head of a steaming retort, or similar opening, and 2 designates a plate or door adapted to close the opening in the head 1.

A packing 3 is preferably provided between the head 1 and plate 2. This packing may be conveniently carried in a dovetail slot formed in the plate 2, and the retort head may be provided with a rim or sharpened edge 4 to make contact with the packing 3. The door or plate 2 is preferably 40 connected to the retort in such manner as to be swung to open or closed positions. A hinge 5 conveniently serves this purpose.

For locking the door or plate to the retort head, the door or plate 2 is provided with a 45 plurality of locking levers 6. The retort head is provided with an inner shoulder or shoulders 7 with which the ends of the locking levers 6 are adapted to engage, in locking position, to hold the door or plate 2 50 locked.

The locking levers 6 are pivotally connected to the door 2, as by means of U-bolts 8 passing through slots 9 in the locking levers 6. These slots 9 are preferably elongated to permit of radial extension, and the 55 reverse, of the locking levers 6.

The locking levers 6 are adapted to be radially extended, and the reverse, in order to bring their ends under the shoulder or shoulders 7, and in this position to be turned 60 on their pivots 8 in order to press the door against the retort head and close the opening against escape of fluid. To this end the locking levers 6 preferably have their inner ends connected to a single disk or plate 10 so that all of the locking levers may be moved together. The plate 10 is given axial movement by suitable means, as a shaft 11. This shaft 11 is screw-threaded and preferably 65 engages a nut 12 having bearing upon the plate or door 2. The disk 10 is conveniently carried upon a reduced end 13 of the shaft 11, and the connection between the disk 10 and the shaft 11 is such that the shaft may 70 turn without turning the disk.

A washer and cotter pin 14 serve to hold the disk 10 upon the reduced portion 13 of the shaft.

The nut 12 is rotatable in its bearing in the door or plate 2, and between the nut 12 80 and the disk 10 there is a pin and slot connection 15. Turning movement of the nut 12 is therefore communicated to the disk 10. The levers 6 being connected to the disk 10 by means permitting of the turning movement of the disk 10, as, for example, pins 16

(Fig. 2), may be moved by the disk 10 into and out of engagement with the shoulder or shoulders 7 of the head 1. When the disk 10 is in one position (as, for example, a 85 position wherein the levers extend radially therefrom), the arrangement of the parts is such that the ends of the levers 6 engage the shoulder or shoulders 7. By turning the disk 10 the lever is turned in its pivot 8, and 90 is also preferably drawn inward on its pivot 8. As here shown, the combined turning of the levers on their pivots 8, and the inward movement of the levers on their pivots 8, withdraw these levers from behind the 95 shoulders, so that the door may be opened.

A hand-wheel 16 or the like serves for turning the shaft 11, and a handle 17 or other suitable means, serves for turning the nut 12.

Operation: When the parts are in the position shown in full lines in Fig. 2, the door or plate 2 may be placed or swung in posi-

tion to close the opening in the retort head 1. To lock the door in place the nut 12 is turned by the handle 17, thereby turning the disk 10 through the pin and slot connection 15. Turning movement of the disk 10 turns the levers 6 upon their pivots 8 and also preferably causes the levers 6 to move lengthwise upon the pivots 8, and by the combined turning and projecting movement, 10 enter behind the shoulder or shoulders 7 upon the retort head 1. After the ends of the levers 6 are behind the shoulder or shoulders 7, in order to press the door tightly against the edges 4, the screw shaft 15 11 is turned, pushing the disk 10 axially inward, and the inner ends of the levers 6, being pushed by the disk 10, cause the levers 6 to pull through the U-bolts 8 against the door. By continuing to move the screw shaft 11 the door is pressed tightly against the retort head. In this manner the plate or door 2 closes the retort head against escape of fluid. The pivots or U-bolts 8 are adjustable, by means of nuts, to adjust the 20 action of the locking levers 6.

To open the door, the threaded shaft 11 is moved in the reverse direction, viz., axially outward, by turning the hand-wheel 16, the shaft 11, through the disk 10, allowing 30 the levers 6 to turn slightly on their pivots 8, so as to release the pressure upon the shoulder or shoulders 7, and thereupon the nut 12 is turned, by means of the handle 17, thereby turning the disk 10 through the connection 15. The turning movement of the disk 10 around the shaft 11 withdraws the 35 ends of the levers 6 from behind the shoulder or shoulders 7, and the turning movement of the levers 6 on the pivots 8 also 40 form a part of the movement of the ends of the levers 6 from behind the shoulders. After the levers 6 are withdrawn from behind the shoulder or shoulders 7, the door 2 may be moved or swung away from the 45 opening in the retort head to permit access to the retort.

Modifications may be made in the embodiment specifically illustrated and described, without departing from the spirit 50 of the invention.

What I claim is:—

1. In combination, a door and means for fastening the same over an opening, said fastening means comprising a plurality of levers pivotally mounted on the inside of 55 the door, a rotatable part for moving said levers into and out of locking engagement with a shoulder on a part to be closed,

means for rocking said levers to press said door into tight contact with the part to be closed, and means operable from the exterior for rotating said rotatable part, said means for rotating said rotatable part being independent of said lever rocking means.

2. In combination, a door and means for fastening the same over an opening, said fastening means comprising a plurality of levers pivotally mounted on the inside of the door, a rotatable part for moving said levers into and out of locking engagement with a shoulder on a part to be locked, a screw shaft for moving said rotatable part axially for rocking said levers to press said door tightly against the part to be closed, and means operable from the exterior for rotating said rotatable part, said means for rotating said rotatable part being operable independently of said screw shaft.

3. In combination, a door and means for fastening the same over an opening, said fastening means comprising a plurality of levers pivotally mounted on the inside of the door, a rotatable part for moving said levers into and out of locking engagement with a shoulder on a part to be locked, a screw shaft for moving said rotatable part axially for rocking said levers to press said door tightly against the part to be closed, and a rotatable nut in which said screw shaft turns, said rotatable nut having a connection with said rotatable part, whereby said rotatable part may be turned by a turning movement of said nut, and an exterior operating part on said rotatable nut.

4. In combination, a door and means for fastening the same over an opening, said fastening means comprising a plurality of levers, a rotatable disk to which said levers are connected, said levers being movable by rotation of said disk into and out of locking position, a manual part for rotating said disk, and means for rocking said levers, when in locking engagement, to press the door tightly against the part to be closed, said manually operated part for moving the levers into and out of locking engagement being independent of the means for rocking the levers for pressing the door tightly against the part to be closed.

In witness whereof, I have hereunto signed my name in the presence of two subscribing witnesses.

FRANK LOUIS MILLER.
